UNITED STATES PATENT OFFICE

NICHOLAS MARRION, OF NEW YORK, N. Y.

CHANGE CARRIER

Application filed July 1, 1931. Serial No. 548,142.

This invention relates to improvements in change carrying and delivering devices of the character worn by conductors on street cars and by other persons for the purpose of readily making change.

The object of this invention is to provide a novel, small, and efficient change carrying and dispensing device for the use of persons receiving and handling money to enable them to quickly and accurately supply the proper change for the same.

Another object of this invention is to provide a device which will be strong and durable and into which coins may be readily placed and easily discharged therefrom.

Still another object of this invention is to provide a coin guide means particularly adapted to change carriers of such a character that the coin can be guided to and entered in the coin drop unerringly and with facility to promote rapidity in the movement.

With these and other objects in view this invention consists in the novel construction hereinafter described, illustrated in the accompanying drawings and set forth in the claims hereunto appended, it being understood that various changes in form, proportion, size and minor details of construction within the scope of the claims may be resorted to without departing from the spirit or sacrificing any of the advantages of the invention, still for the purpose of showing a preferred embodiment thereof, reference is had to the accompanying drawings in which like numerals designate like parts and in which

Figure 1 is a front elevational view of a change carrier with parts broken away.

Figure 2 is a fragmentary side elevational view of the change carrier with my improved chute positioned thereon.

Figure 3 is a sectional view taken through the center of Figure 2 on line 3—3.

Figure 4 is a perspective view of the change chute.

Figure 5 is a back view of the chute with a number of coins placed therein.

Figure 6 is a sectional view taken on line 6—6 of Figure 5.

The advantages of my invention become

obvious when one reviews and considers the coin devices in present use. These devices are as a general rule used by conductors on street cars, newspaper boys, and other persons that receive small change and must work quickly. The change carriers of the ordinary type are provided with coin slots in the upper end thereof, said slots being large enough to permit the passage of only one coin at a time thereby making it a very slow and tedious process when one has a great number of coins to insert successively. In the case of the street car conductors, especially in the one-man cars, although the conductors can make change readily enough they cannot deposit the coins in the carrier with either ease or speed. Now, to overcome such difficulty, I have provided a chute into which, a great number of coins may be placed, and fed into the slot without any aid whatsoever from the conductor or wearer of the coin carrier, without jamming or choking the throat of the machine, thereby saving much time and labor.

Referring more specifically to the drawings in detail, the invention comprises a change carrier 32 having a neck portion 33, a top cover 34, a coin slot therein 35 and a coin ejector 36. The improved coin chute which constitutes the novel invention in this instance, has a body portion 37, a chute member 38, an extension 39, a neck portion 40 and a throat 41. To the under side of the chute is secured a check member 43 which extends upwardly and over the edge and into the path of the coins. The neck portion of the present device is provided with a set screw 44 for securing said chute to the neck portion of the change carrier 32.

My improved coin chute as herein shown is designed so as to be fitted to change carriers such as those already in use, but, can be made directly to the change carrier when manufactured.

While I have shown only one type of change carrier, it is to be understood that my improved device may be attached to any make of change carriers, or, may be made directly thereto.

In operation the neck portion 40 of the chute is positioned over the neck portion 34

of the change carrier and secured thereto by the set screw 44. When a large stack of coins, as shown in Figures 5 and 6, are placed within the concaved chute 38 they are checked by the spring member 43, and when the first coin slides off the extension 39 and from under the check spring 43, the weight of the succeeding coins forces the preceding coin into the slot. A like operation is performed in rapid succession until all the coins have passed into the carrier. While I have shown only one check spring, it is to be understood that I may employ a plurality of such means, without departing from the spirit of the invention.

15 Having thus described my invention what I claim as new and desire to secure by Letters Patent in the United States of America, is:

1. A filler for a coin container comprising a coin guiding chute into which a plurality of coins may be placed and said chute being provided with a projection for checking the rush of coins into said container.
  2. A filler for a coin container comprising a change guiding chute, said chute having a concave bottom with the extended inner end elevated slightly above said container, a check member on one side of said chute, said check member extending into path of said coins, and in spaced relation with respect to the extended inner end of said chute.
  3. A filler for a coin container comprising a coin guiding chute into which a plurality of coins may be placed, said chute being provided with a projection for checking the rush of the coin into said container and having a neck portion and means of securing said filler to said coin container as shown and described.
- 40 In testimony whereof I have signed my name to this specification.

NICHOLAS MARRION.
